UNITED STATES PATENT OFFICE.

DAVENPORT C. MCCOY, OF JACKSONVILLE, ILLINOIS.

BRIDLE-BIT ATTACHMENT.

SPECIFICATION forming part of Letters Patent No. 278,576, dated May 29, 1883.

Application filed December 5, 1882. (No model.)

To all whom it may concern:

Be it known that I, DAVENPORT C. MCCOY, a citizen of the United States, residing at Jacksonville, in the county of Morgan and State of Illinois, have invented certain Attachments to the Bits of Bridles used upon Horses, of which the following is a specification.

My invention consists of a cord made of any flexible material—such as cotton, hemp, flax, leather, rawhide, india-rubber, or wire or similar material—passing under the upper lip of the horse and over the upper teeth, each end of the cord passing through a hole in the ring at each end of the bit. One end of the cord has an iron loop fastened to it, and the driving-line is buckled through both the bit-ring and the iron loop at the end of the cord. The other end has a similar iron loop with a swivel, into which that end of the cord passes, movable along the cord and fastened, and made stationary by the use of a thumb-screw, by which the length of the cord may be adjusted to the horse's mouth, and the other driving-line is buckled through both the bit-ring and the swivel-loop. When the bit is adjusted to the bridle and the cord passed under the upper lip of the horse, as aforesaid, and driving-lines fastened, as aforesaid, a sharp pull on the lines draws the cord over the upper teeth 30 against the gums of the horse, and enables the driver to completely subdue the horse.

Drawing 1 shows the bit with attachment. A is the cord to pass under the upper lip of the horse. B B are the holes in the bit-rings through which the cord passes. C is the iron loop into which one driving-line is buckled,

also to the bit-ring. D is the iron loop at the other end of the cord, into which the other driving-line is similarly buckled. E is the swivel of the said loop D, around the cord 40 and movable along the cord. F is the thumb-screw with which to fasten it at any point along the cord when adjusted to the size of the horse or his mouth.

Drawing No. 2 shows the bit and attachment in the horse's mouth.

Having fully described my invention, what I desire to claim and secure by Letters Patent is—

1. In a bridle, the combination, with the 50 driving-lines, of the cord A, adjustably attached to the lines, and adapted to pass around the upper jaw of the horse, beneath the upper lip, all substantially as set forth.

2. The combination, with the driving-lines 55 and the bit-rings, of the cord A, passing through said rings, and adjustably attached to the driving-lines, all substantially as shown and described.

3. A bridle provided with the attachment 60 A, adjustably secured to the driving-lines by means of the devices E and F, all substantially as set forth.

4. The combination, in a bridle, of the driving-lines, the bit, the bit-rings, and the attachment A, all arranged and operated substantially as described.

DAVENPORT C. MCCOY.
